INK FOUNTAIN DIVIDER

Stephen A. Lerch, Milwaukee, Wis.

Application May 2, 1949, Serial No. 90,960

6 Claims. (Cl. 101—210)

1

This invention relates to improvements in ink fountain dividers of the type used to keep ink of different colors separated in the fountain.

Such dividers have heretofore been designed only to prevent ink of different colors from running together when in the fountain. They did not prevent ink of different colors from running together after it had been deposited on the fountain roller and while being transferred thereby.

It is an object of this invention, therefore, to provide an ink fountain divider which not only prevents ink of different colors from running together in the fountain but also treats the fountain roller so that such ink deposited thereon will not run together during transfer.

Another object of the invention is to provide an ink divider which automatically adjusts the fountain roller engaging portion thereof with respect to the contour of the fountain roller during rotation thereof and during adjustment of the fountain blade.

These objects are obtained by providing the divider with a reservoir for ink separating fluid and connecting such reservoir with the fountain roller engaging pad. A needle valve may control the flow of fluid to the pad so that it is kept in a state of saturation sufficient to deposit a light film of such fluid on the fountain roller. The film so deposited will prevent the ink from running together on the fountain roll while it is being transferred.

A spring-biased plate carried by the divider resiliently urges the lower end of the fountain roller engaging pad into constant contact with the surface of such roller. Thus such pad will remain in proper contact with the face of the roller as such face and divider move relatively toward and away from each other during rotation of an uncentered roller or adjustment of the fountain blade.

The novel features, which are considered characteristic of the invention, are set forth with particularity in the appended claims. The invention itself, however, both as to its organization and its method of operation, together with additional objects and advantages thereof, will best be understood from the following description of a specific embodiment when read in connection with the accompanying drawing, in which:

Fig. 1 is a view in side elevation of a divider

2

embodying the present invention with the fountain and fountain roller shown in section;

Fig. 2 is an enlarged fragmentary view in side elevation of the ink divider of Fig. 1 with parts broken away and shown in section for the sake of clarity and illustration; and

Fig. 3 is a view in end elevation taken on line 3—3 of Fig. 2.

Referring to the drawing by reference numerals, the divider 16 is releasably mounted in an ink fountain 10 of well-known design associated with a fountain roller 12 and having an adjustable fountain blade 14. The edge of fountain blade 14 is adjusted with respect to the roller by means well known in this art and therefore not shown or described herein. The ink divider 16, as is shown in Fig. 1, is mounted on fountain blade 14 with its bottom resting thereon and with its forward end in engagement with the fountain roller 12. As is the usual practice, a pad 17 on and considered a part of the divider makes the actual sealing contact with the surfaces of roller 12 and blade 14. Pad 17 preferably consists of a strip of felt extending as an integral unit along the roller engaging face of the divider.

In the embodiment illustrated, divider 16 is an aluminum casting which has side walls 18, the front edges of which are curved to conform with the periphery of fountain roller 12. Extending between the side walls is a front wall 20, the forward face of which is spaced rearwardly from the forward edges of such walls to provide a pad receiving and holding recess. Front wall 20 merges with a bottom 22 also extending between side walls 18. The lower surface of bottom 22 is spaced upwardly from the bottom edge of side walls 18 to provide a pad receiving and holding recess. Side walls 18 and bottom 22 are joined to terminate in a hook-like mounting arm 26 which carries a wing bolt 27. A mounting arm 26 extends around the outer edge of and engages opposite sides of fountain blade 14 to rigidly position divider 16 in proper adjusted location with respect to the fountain. Side walls 18, front wall 20, and rearwardly upwardly sloping bottom 22 cooperate to define an open top reservoir for ink separating fluid.

Bottom 22 is provided with an undercut recess 28 which extends to the front face of front wall

20. This recess provides space for the pad plate operating spring as well as forming part of a channel for connecting reservoir 24 with pad 17. Longitudinally extending grooves 30 are formed in the opposite inner faces of side walls 18 below bottom 22. These grooves provide a track for slidably guiding a pad plate 32, the forward edge of which engages with pad 17 at the juncture of its roller engaging portion and its fountain blade engaging portion. The forward end of pad-engaging plate 32 may be turned down as shown in Fig. 2 and provided on the upper surface thereof with grooves 33. Ink separating fluid passing through channel 28 runs along the upper surface of plate 32 and grooves 33 enable such fluid to more readily reach pad 17 and be absorbed thereby. In order that the pad engaging plate 32 may also maintain a constant pressure between roller 12 and such juncture of pad 17, such plate is resiliently urged outwardly of divider 16 by a coil compression spring 34 reacting between the rear end of recess 28 and a place on plate 32 intermediate its ends.

To control the communication or channel between reservoir 24 and channel 28, bottom 22 is provided with a tapped opening 36 in which is threadedly mounted an adjustable nipple valve 38 of standard construction. Nipple valve 38 has an inlet 40 communicating with reservoir 24 and an outlet 42 opening into channel 28. By rotation of a knurled handle 40, the channel from the reservoir to the pad may be completely closed or opened to the desired amount. For keeping the contents of the reservoir free from dirt or other undesirable material, a cover 46 has sides which 35 overlappingly engage the side walls 18 to hold the cover in place on divider 16. The forward end of the cover is slotted, as indicated at 48, to accommodate the shaft of the needle valve.

When initially mounting divider 16 in fountain blade 14 the roller engaging portion of pad 17 is compressed so that it is seated within the pad recess on the forward face of the divider. Wing nut 27 is then clamped to keep the divider in this position, such clamping action also compressing the fountain blade engaging portion of the pad 17 into the pad recess on the bottom of the divider. At the same time plate 32 is moved inwardly from the position shown in Fig. 2 and spring 34 compressed and placed under tension. 50 This tends to change the contact pressure at the juncture on pad 17. Also, as fountain blade 14 is adjusted so that its forward edge is properly positioned relative to fountain roller 12, there will be a change in the contact pressure on such juncture. However, such changes are offset and a proper constant pressure maintained by the continuous pressure asserted by compressed spring 34 acting through sliding plate 32. An ink separating fluid, such as paraffin oil or a mixture of paraffin oil and type wash, is put in reservoir 28 and needle valve 38 opened to permit such fluid to flow from reservoir 24 through channel 28 to pad 17. This fluid is absorbed by the pad and when the lower area of its roller engaging portion is saturated a thin film-like strip of such fluid will be deposited on roller 12 as it rotates. Such strip will continuously extend around the roller to the top of pad 17 during the rotation of roller 12. Some of the fluid in such strip will be transferred from the fountain roller to the ductor roller. However, that amount of fluid in the strip which is not transferred to the ductor roller, evaporated or otherwise lost will again be picked up by pad 17. Hence, after 75

10 the roller engaging portion of pad 17 is entirely saturated, it is only necessary to replace the lost portion of the fluid. This is accomplished by regulation of valve 38. The film-like strip of ink separating fluid so deposited on roller 12 keeps inks of different colors also deposited on the roller from running together. Such effect may also be present to some degree as the ink and film-like strip are transferred in the printing process to other rollers.

15 When the divider is not in use, it may be readily removed from the ink fountain and cleaned. The pad plate 32 readily slides forwardly out of grooves 30 carrying with it spring 34, thus exposing channel 28 and outlet 42 for ready and easy cleaning.

20 Although only one embodiment of the invention is shown and described herein, it will be understood that this application is intended to cover such changes or modifications as come within the spirit of the invention or scope of the following claims.

I claim:

1. In an ink fountain divider for applying a film of ink separating liquid on the fountain roller, a fountain roller engaging absorbent pad carried by said divider and separated from a reservoir in said divider, a reservoir within said divider containing ink separating fluid, and a channel between the lower end of said reservoir and said pad whereby said fluid is continuously applied to said end of said pad and deposited thereby in the form of a light film on the fountain roller, and means for regulating the flow of fluid from said reservoir to said channel.
2. In an ink fountain divider having a front wall and a bottom, a fountain roller and fountain blade engaging pad carried by said divider, a pad engaging plate resiliently slidably carried by said divider beneath said bottom and having an edge facing and engaging said pad at the juncture of the roller and blade engaging portions thereof to maintain said pad in constant pressure relationship with said roller.
3. In an ink fountain divider having a front wall and a bottom, a reservoir for ink separating fluid in said divider, a roller engaging pad adjacent said front wall and bottom, a spring-biased plate slidably carried by said divider below said bottom and having an edge facing and continuously urging said pad toward said roller, and a channel from said reservoir to the top of said plate whereby ink separating fluid in said reservoir is conducted to said pad along said plate.
4. An ink fountain divider as claimed in claim 3 in which the pad engaging end of said plate is provided with grooves for guiding ink separating fluid to said pad.
5. In an ink fountain divider having spaced side walls, a front wall between said side walls, a bottom between said side walls and spaced above the lower edges thereof, said walls and bottom defining a reservoir for ink separating fluid, oppositely related grooves in said side walls below said bottom, a recess in the outer side of said front wall, a pad engaging plate slidably mounted in said grooves, a compression spring having one end attached to said plate and its other end abutting against the inner end of said recess, a controlled opening between said reservoir and said recess, and a fountain roller and fountain blade engaging pad engaged by the forward end of said plate.
6. In an ink fountain divider having spaced

side walls, a front wall between said side walls, a bottom between said side walls and spaced above the lower edges thereof, said walls and bottom defining a reservoir for ink separating fluid, a recess in the outer side of said bottom extending to the outer surface of said front wall, a controlled opening between said reservoir and said recess, and a fountain roller and fountain blade engaging pad extending along said front wall and said bottom and receiving said fluid from 10 said recess.
